E. A. PETERSON

CASEMENT SASH

Filed May 31, 1922

UNITED STATES PATENT OFFICE.

ERNEST A. PETERSON, OF OAKLAND, CALIFORNIA.

CASEMENT SASH.

Application filed May 31, 1922. Serial No. 564,792.

To all whom it may concern:

Be it known that I, ERNEST A. PETERSON, a citizen of the United States, residing at Oakland, in the county of Alameda and State of California, have invented certain new and useful Improvements in Casement Sashes, of which the following is a specification.

My invention is an improvement in windows, particularly of the type known as casement windows.

The object of my invention is to provide a means of locking the window in any desired open position in an efficient and positive manner as will subsequently be described.

Referring to the annexed drawing:

Figure 1 is a perspective view of my window.

Figure 2 is a transverse sectional view of my window with the sash in closed position.

Figure 3 is a side view of the lower rider.

Figure 4 is a side view of the upper rider.

Referring more particularly to the drawing, the numeral 1 indicates a casement and 2 a sash. The casement 1 comprises horizontal members 3 and 4 and vertical members 5 and 6. The sash 2 comprises vertical members 7 and 8 joined by horizontal members 9 and 10.

In the members 3 and 4 are secured horizontal V-shaped slideways 11 and 12 respectively. A V-shaped rider 13 travels in the slide 11 and a rider 14 travels in the slide 12. The rider 13 has an upstanding post 15 which projects into the lower end of the member 7 within a socket 16. The rider 14 has a depending post 17 which extends into a socket 18 in the upper end of the member 7. A slot 19 is cut in the member 7 running from front to rear, and a vertical bore 20 joins the slot 19 and socket 16. A rod 21 fits within the bore 20, the lower end of said rod contacting with the post 15 and the upper end projecting within the slot 19 and having a cap 22 thereon.

A lever 23 is pivoted in the upper end of the slot 19 and has projecting handles 24 and 25 to actuate said lever. A downwardly projecting stud 26 has a roller 27 pivoted thereto, said roller being adapted to engage the cap 22 of the post 21.

A spring 28 surrounds the post 17 of the rider 14 and is positioned between the

upper end of member 7 and the rider 14. A rabbet in the upper surface of the sash allows for this arrangement.

A link 30 is pivoted to the members 3 and 10 and a link 31 is pivoted to the members 9 and 4, thus linking the sash and casement together. Suitable locks 32 and 33 on the inner and outer sides of the member 8 lock the sash in its closed position.

The sash is locked in any open position in the following manner. The handle 24 is swung downwardly which moves the stud 26 and roller 27 into engagement with the cap 22 forcing the rod 21 downwardly and wedging the rider 13 in the slide 11. This downward movement also raises the sash slightly against the tension of the spring 28 which spring holds the rider 14 wedged firmly in the slide 12. To release the sash the handle 25 is moved downwardly which swings the roller 27 away from the cap 22 and releases the pressure on the riders 13 and 14, when the sash may be moved as desired.

Having described my invention, I claim:

1. A window comprising a casement and a sash, links pivoted to the casement and the sash, guide grooves in the casement, riders in said guide grooves, said riders having posts projecting therefrom which fit into sockets in said sash, a lever pivoted in said sash, and means connecting said lever and one of said posts whereby the riders may be wedged in the guide grooves.

2. A window comprising a casement and a sash, links pivoted to the casement and the sash, guide grooves in the casement, riders in said guide grooves, said riders having posts projecting therefrom which fit into sockets in said sash, a lever pivoted in said sash, said lever having a stud projecting therefrom, a rod engaging the post of the lower rider and adapted to be engaged by said lever stud, a spring encircling the upper rider post and positioned between said sash and said rider.

3. A lock for casement windows having riders on the sash traveling in slides on the casement comprising means to increase the normal distance between said riders, said means including a manually operated lever.

In testimony whereof I affix my signature.

ERNEST A. PETERSON.
